BOAT HULL

Jack Davidson, 3316 E. Annadale, Fresno, Calif. 93725

Filed Mar. 22, 1972, Ser. No. 237,232

Term of patent 14 years

Int. Cl. D12—06

U.S. Cl. D71—1 Q

FIG. 2.

FIG. 3.

FIG. 4.

FIG. 5.

FIG. 6.

FIG. 7.

FIG. 1 is a top plan view of a boat hull showing my new design.

FIG. 2 is a starboard side elevation thereof, the port side being identical thereto.

FIG. 3 is a bottom plan view thereof.

FIG. 4 is a bow elevation thereof.

FIG. 5 is a stern elevation thereof.

FIG. 6 is a section taken on line 6—6 of FIG. 1.

FIG. 7 is an offset section taken on line 7—7 of FIG. 1.

I claim:

The ornamental design for a boat hull, as shown and described.
